UNITED STATES PATENT OFFICE.

WILLIS B. BURNS, OF SYRACUSE, NEW YORK.

CAR-COUPING.

SPECIFICATION forming part of Letters Patent No. 507,781, dated October 31, 1893.

Application filed July 17, 1893. Serial No. 480,707. (No model.)

To all whom it may concern:

Be it known that I, WILLIS B. BURNS, a citizen of the United States, residing at Syracuse, in the county of Onondaga and State of New York, have invented certain new and useful Improvements in Car-Couplings, of which the following is a specification.

My invention relates to car couplers of the Janney type wherein each draw head is furnished with a pivotal block or L-shaped knuckle, the knuckle of two draw heads being adapted and arranged to swing or turn about their pivot pins and to engage with each other when the draw heads are brought together.

The invention consists in various novel features and combinations hereinafter set forth, prominent among which are a gravitating latch for locking the knuckle against movement, and a lever actuated by a cam or rib on the latch and serving to swing the knuckle about its pivot and to open the coupling.

In the accompanying drawings,—Figure 1 is a perspective view of one draw-head of my improved coupler, portions being broken away to show the construction and arrangement of the working parts. Fig. 2 is a similar view, but with the knuckle thrown outward or opened instead of closed and locked, as in Fig. 1. Fig. 3 is a bottom plan view, with the draw head in section, the knuckle being shown in its closed and locked position by full lines, and in its opened position by dotted lines. Fig. 4 is a perspective view of the knuckle, looking upward from beneath; and Fig. 5, a perspective view of the gravitating latch and of the lever by which the knuckle is thrown outward.

The objects of my invention are, to produce a simple and efficient coupler, which shall automatically couple and lock when two draw-heads are thrown together; in which the knuckles may not only be unlocked, but may also be thrown out of locking position, so that there shall be no necessity for taking hold of and swinging the knuckles outward, nor for holding back the locking device after it is released and until the cars are drawn apart; and in which there shall be no springs or small and delicate parts.

With these ends in view I construct my coupler in the manner illustrated in the an-

nexed drawings, it being of course understood that two draw heads, with their attendant parts, are necessary to constitute the complete coupling device. But one draw head is shown in the drawings, since the second is a duplicate of the first, and the general plan of construction and operation is well known and understood.

A indicates a draw head, which will or may vary in form and dimensions according to its intended use for freight or for passenger cars, as is the case with other car couplers. The forward or outer end of the draw head is of the general U-shape common to its class, and a knuckle, or L-shaped block B is hinged or pivoted in one arm of the U-shaped end, and arranged to swing about a heavy vertical pin C, as shown in Figs. 1, 2 and 3. The general shape of the knuckle B is similar to that of the knuckles of existing couplers of this type; that is to say, its forward arm a is formed with a recess m to receive an ordinary link, and is perforated for the insertion of a common coupling pin, so that a car with this draw head may be readily coupled with a car having the ordinary link and pin coupling. The rear or inner arm b, of the knuckle B is, however, rounded off or beveled on its rear and upper face, to enable it to ride beneath and to lift a gravitating latch or locking dog D, shown in Figs. 1, 2, 3 and 5. To facilitate the entrance and movement of the arm b beneath the latch or dog D, the forward under portion of the latch is also beveled or rounded, as shown in Figs. 1, 2 and 5. The latch or dog D is a quite heavy and substantial block, which may be cast or forged, as deemed best, the pivotal portion of which reaches from one inner wall of the neck or shank of the draw head to the other, so as to receive direct and firm support from the draw head and to relieve its pivot pin E of undue strain. The forward end of the latch or dog is made slightly wedging in form, or somewhat narrower on its lower than its upper face, so as to come to a firm bearing against a corresponding bearing face c in the draw head, and against the forward face of arm b of the knuckle B, when the latter is locked in place.

As shown in Figs. 1, 2 and 3, the forward end of the latch or dog extends somewhat beyond the sweep or line of movement of the

outer end of arm *b* of the knuckle *B*, and when said arm is swung back or inward, drops down in front of and securely locks said arm, and consequently the knuckle, against movement about its pivot pin *C*. The latch or dog 5 is mounted upon a horizontal stem or rock-shaft *E*, which is journaled on the side walls of the draw-head, and which is made of polygonal form in that portion of its length which 10 is within the body of the latch or dog, so that neither may move or rock independently of the other. It is obvious that a key or feather, or a through-pin might be used to thus connect the latch or dog and its rock-shaft, but 15 the polygonal body and opening are deemed the better construction. The rock-shaft *E* projects outward from the side of the draw head, and may receive or be connected with any suitable hand lever or other device for 20 turning it.

In Figs. 1 and 2 I have represented the rock-shaft as furnished with an extension rod *F*, terminating in a lateral arm or hand piece *d*. Such an arrangement contemplates actuation 25 of the latch from the side of the car, and will be especially suitable for freight cars, but for passenger cars it will ordinarily be preferable to arrange an upright hand lever upon the car platform, and to connect it by chain, 30 link or otherwise with an arm on the rock-shaft.

The central portion or hub of the knuckle *B* is formed with recesses *e e* at top and bottom, the end walls or shoulders of which engage with or abut against similar shoulders, 35 or lugs *f*, formed upon the draw-head, and thereby limit the throw or movement of the knuckle *B* about its pivot.

Projecting downwardly and rearwardly 40 from the hub or pivotal portion of latch or dog *D* is a rib *g*, which is inclined or curved obliquely to the pivot action of the latch, but has its outer edge made concentric with said axis, or approximately so.

G indicates a lever, the two arms of which are somewhat out of alignment as shown in the drawings, thus producing an elbow lever; but though this form is advantageous, it is not essential, and may be replaced by a 45 straight lever. Lever *G* is fulcrumed upon a stud or pin *h*, which may be cast upon the bottom wall of the draw head opening, or may be a separate bolt. The rear end or arm of lever *G* rests against the side of rib *g* of the latch 50 *D*, near the forward end of said rib, as the parts stand when the knuckle is swung in and locked. The forward arm of said lever is formed with a curved edge or face *i*, which bears against a rib *j* formed upon the lower 55 side of arm *b* of knuckle *B*; and at the extreme outer end of the forward arm of said lever there is formed a nose or hook *k*, which, as the knuckle reaches the limit of its outward movement, engages with the end wall of a deepened portion *e'* of the lower recess *e*, and prevents further movement of the lever *G*. This 60 engagement of the hook or nose *k* also insures

the return of the lever to its normal position when the knuckle is swung back to place. The descent of latch or dog *D* is limited by 70 a shoulder or stop *l*, seen in the bottom view, Fig. 3.

Two draw heads being constructed and fitted with parts as above set forth, their operation is as follows: Assuming that the parts 75 are in the position shown in Fig. 1, the rock-shaft *E* is turned to lift the latch or dog and thereby to unlock the rear arm *b* of knuckle *B*. As the latch *D* swings upward its curved rib or cam *g*, acting upon the rear end of lever *G*, throws the forward end of said lever laterally against the rib *j* of knuckle *B*, causing 80 said knuckle to swing about its pivot and to assume the position indicated in Fig. 2, and by dotted lines in Fig. 3. The rock-shaft *E* being then released, the latch *D* drops back by gravity to the position shown in Fig. 1, aided by the weight of hand piece *d*, if that be used, leaving the knuckle in the forward or open position shown in Fig. 2. The two 85 cars are now brought together, and the forward arm *a* of each knuckle, bearing against the rear arm *b* of the other knuckle, causes each to swing about its pivot, the arms *b* riding beneath and lifting the respective latches 90 *D*, which drop down in front of and firmly lock the arms *b* as soon as the arms complete 95 their backward movements. It will thus be seen that without passing or reaching between the cars and without directly touching 100 the knuckle, each member of the coupling may be quickly and certainly unlocked, opened, and left open; and when the two are brought together they will automatically couple and lock. It will also be seen that the 105 unlocking and opening of the knuckles can be effected equally well whether the cars are coupled or uncoupled at the time. The latch or locking dog *D* having a solid bearing against the wall of the draw head, and being 110 itself strong and heavy, affords a very secure lock for the knuckle; while its wedging form causes it to bear closely against the draw-head and against the rear arm of the knuckle, thereby preventing play or lost motion, which 115 play always conduces to breakage or disarrangement. The strain or pressure of the knuckle *B* upon the latch or dog being at right angles to the movement of the latter, there is no tendency to force the latch from 120 its locking position, and hence there is no liability of the coupling becoming accidentally unlocked.

All the parts are of ample proportions, strong, and simple, and the liability to 125 disarrangement attending the use of springs and delicate mechanism is avoided.

It will be observed that the locking dog or latch *D* has a simple rising and falling movement, without lateral or spiral action, and that when in locking position it bears firmly 130 against the tail of the knuckle at one side and against the wall of the draw-head at the other side, owing to its slightly wedging form.

When in locking position its weight is almost wholly at one side of and in horizontal plane with the rock-shaft which constitutes its pivot, so that while its weight tends constantly to hold it in locking position, the block is not free to swing or move by reason of sudden starting, stopping or jolting of the car, as would be the case were it a pendulous block. So, too, it will be noted that I avoid the use of springs to open the coupling when the locking dog is withdrawn, and require no catches or detents to hold the locking dog or latch in one or another position for coupling or uncoupling.

15 The combination of the direct-moving locking dog or block with the knuckle and intermediate lever, produces an exceedingly strong, simple and efficient coupling, which may be operated with ease and certainty under all 20 conditions, and is not liable to derangement or injury through the severe usage to which car couplings are inevitably subjected.

Having thus described my invention, what I claim is—

25 1. In combination with a draw-head, a knuckle mounted and arranged to swing about a vertical pivot therein, a latch for locking said knuckle arranged to swing about a horizontal pivot passing transversely through the 30 draw-head, and a lever located between the knuckle and the latch and serving to transmit motion from each to the other, substantially as and for the purpose set forth.

2. In combination with draw-head A and 35 horizontally-swinging knuckle B, vertically

swinging latch D carried by a transverse pivot E; and lever G located between the knuckle and the latch and serving to transmit motion from one to the other.

3. In combination with a draw head A and 40 a knuckle B pivoted therein and provided with rib *j*; latch D provided with rib *g*; and lever G pivoted in the draw head and bearing at opposite sides of its fulcrum against the ribs *g* and *j* respectively. 45

4. In combination with a draw head A and with a knuckle B having a limited range of movement therein and provided with recess *e'*; latch D provided with rib *g*; and lever G, provided with hook or nose *k* to enter said 50 recess, substantially as and for the purpose explained.

5. In combination with a draw-head, a knuckle or L-shaped block pivoted and arranged to swing horizontally therein, a horizontally-pivoted gravitating latch for locking said knuckle, one arm of the knuckle being beveled to ride beneath and lift the latch; and a lever located between the latch and the knuckle, all substantially as described and 55 shown, whereby the coupling may be opened and closed without the aid of springs and catches other than the locking block.

In witness whereof I hereunto set my hand in the presence of two witnesses.

WILLIS B. BURNS.
